United States Patent Office

Des. 229,593
Patented Dec. 18, 1973

229,593

SOFA

Morris F. Fisher, Carmel, Ind., assignor to Jackson
Chair Company, Inc., Danville, Ky.

Filed May 30, 1972, Ser. No. 258,201

Term of patent 14 years

Int. Cl. D6—01

U.S. Cl. D6—63

Fig. 1

Fig. 2

FIG. 1 is a perspective view of a sofa showing my new design, and directed downward and toward the front and one side of the sofa; and

FIG. 2 is a perspective view directed downward and toward the rear and other side of said sofa.

I claim:

The ornamental design for a sofa, as shown.
